TOE GRIP SAFETY SKATE

Daniel S. Williams, Pottstown, Pa.

Application February 12, 1958, Serial No. 714,845

4 Claims. (Cl. 280—11.19)

This invention relates to roller skates particularly of the armoured type wherein a shield extends around the toe portion of the skate, and in particular a roller skate having a platform formed with toe and heel portions with the portions slidably connected to provide longitudinal adjustment as to size, and with a shield, U-shaped in plan extended around the toe portion and having a toe stop at the bottom of the forward end. The heel portion of the skate is provided with a heel stop that extends from the trailing end. The skate is retained in position on a shoe by elongated toe and heel straps having spaced notches in the edges, the toe strap extending through slots in side walls of the shield and the heel strap having a T-shaped head or T-formation on one end with a slot and notches at the sides of the opposite end for receiving the T-formation or T-shaped head to rigidly secure the skate to a shoe without using buckles or other fastening elements.

The purpose of this invention is to provide a roller skate of an improved design wherein the roller skate is retained on a shoe on the foot of an individual by strap forming locking keys and wherein a complete guard or shield is provided around the toe.

Various types of fastening elements have been used for retaining roller skates in position upon shoes, and the like; however, without permanently attaching roller skates to shoes it is difficult to retain the skates in operative positions upon the shoes.

With this thought in mind this invention contemplates a roller skate having toe and heel portions adjustably connected in which the toe portion is provided with a shield U-shaped in plan and having a toe stop at the forward end and in which toe and heel straps are formed with locking keys for definitely retaining the skates in positions on shoes and the like.

The object of this invention is, therefore, to provide a roller skate in which shoes on the skate are protected with a continuous U-shaped shield.

Another object of the invention is to provide means for retaining a roller skate in position upon a shoe or a foot of a wearer without using conventional buckles and other similar fastening elements.

A further object of the invention is to provide a roller skate in which means is provided for positively retaining the skate in position on a shoe or the like in which a skate is provided of an entirely different design.

A still further object of the invention is to provide a roller skate having an armour-like shield around the forward end with fastening elements for retaining the toe and heel upon corresponding parts of a shoe in which keys are held in slots obviating the use of buckles and other similar fastening elements in which the skate is of a simple and economical construction.

With these and other objects and advantages in view the invention embodies a platform having a toe section mounted on wheels, a heel section also mounted on wheels and slidably connected to the toe section, the heel section being provided with a transversely disposed

2

plate forming a stop, the toe section being provided with a U-shaped shield having an inclined forward surface and having a toe stop at the lower end and toe and heel straps having notches in the edges positioned to coat with slots for securing the skate upon a shoe or the like.

Other features and advantages of the invention will appear from the following description taken in connection with the drawing, wherein:

Figure 1 is a side elevational view of the improved skate.

Figure 2 is a plan view of the skate with the parts as shown in Figure 1.

Figure 3 is a longitudinal section through the skate taken on line 3—3 of Figure 2.

Figure 4 is a cross section through the forward part of the skate taken on line 4—4 of Figure 1.

Figure 5 is a view illustrating the locking keys and slots of the toe and heel straps of the skate showing ends of the straps separated and with portions of the straps broken away.

Figure 6 is a section showing a modification wherein the rollers of the forward shaft are secured on the shaft by riveting or otherwise upsetting the ends of the shaft.

Referring now to the drawing wherein like reference characters denote corresponding parts the improved roller skate of this invention includes a platform having a forward or toe section 10, a heel section 11 slidably connected to the toe section, a shield 12 secured to ears 13, 14, and 15 extended downwardly from the under surface 20 of the platform of the toe section 10 by rivets 16, a toe strap 17 extended through a slot 18 in a side wall 19 of the shield and through a slot 20 in a side wall 21 of the shield and a heel strap 22 extended through slots 23 of the heel section 11 and having notches 25 in the edges for retaining the end of the strap in a slot 26 in an enlarged section 27 at the opposite end of the strap.

The toe portion is mounted on wheels 28 and 29 that are retained in position on a shaft 30 by depending portions 31 and 32 of the side walls 19 and 21 of the shield 12, and the shaft is mounted in bearings 33 and 34 depending from the lower surface of the platform 10. The inclined forward surface 35 of the shield 12 is provided with a depending flange 36, the lower edge 37 of which provides a toe stop limiting forward tilting movement of the skate.

As illustrated in Figure 6 the ends of a shaft 38, similar to the shaft 30 may be upset or riveted to provide heads 39 that prevent wheels 40, similar to the wheels 28 and 29 being accidentally removed from ends of the shaft. It will be understood that other means may be provided for retaining the wheels on the shaft.

The platform 10 is also provided with an opening 41 that is positioned directly below the toe of a shoe to which the skate is secured. The upper portion of the shield 12 is also provided with a web 42 that provides a cover for the toe of a shoe thereby preventing damage to the outer surface of a toe of a shoe to which the skate is secured.

The key or locking strap 17 of the toe portion of the skate is formed with notches 43 in the sides of one end and 44 in the sides of the opposite end and with teeth 45, between the notches extended through the slots 18 and 20 in the side walls of the shield of the skate, as shown in Figures 2 and 3 whereby the toe of the skate may be positively secured to the toe of the shoe. The key or strap 17 may be pulled through until the skate is definitely secured in position upon the toe of a shoe.

The rear portion of the platform 10 of the toe part of the skate is provided with a bolt 46 that extends through a slot 47 in a tongue 48 extended from the heel section 11 of the skate and by this means the heel section or portion may be adjusted in relation to the toe portion to

correspond with the size of a shoe on which the skate is positioned.

The section 11 is provided with wheels 49 and 50 that are positioned on the ends of a shaft 51 mounted in depending bearings 52 and 53 and on this portion ends of the shaft are upset or riveted over providing heads 54 and 55 that prevent accidental separation of the wheels from the shaft.

The heel portion or section 11 of the platform of the skate is also provided with a depending flange 56 which is provided with a beveled edge 57 providing a scraping portion 58 that forms a heel stop or brake to limit forward movement of the skate when a quick stop is necessary. The portion 11 is also provided with heel locating lugs 59 and 60 that are positioned inside of the slots 23 through which the strap 22 extends and with the heel positioned against the lugs 59 and 60 the end 61 of the key or strap is drawn through the slot 26 and by pulling on the end 61 the teeth 62 are drawn through the slot 26 until the strap is tight around the ankle of a foot on which the skate is positioned.

The heel portion 11 is also provided with a slot or opening 63, which like the opening 41 in the toe portion reduces the weight of the platform of the skate.

The skate may be provided in different sizes and with the parts designed and assembled as illustrated and describe the toe of a shoe may be placed in the forward end of a skate below the strap or key 17 and with the toe secured in position the heel is placed against the lugs 59 and 60 and secured in position by the heel strap 22 the key portion 61 of which is inserted through the slot 26 and drawn tight securing the heel portion of the platform of the skate to the ankle or rear portion of the shoe or foot of a wearer. Should wear develop in the parts the keys may be drawn through the slots to take up play or slack so that the skates are readily retained in fitted positions continuously during use.

The shield 12 not only provides a protector for the toe of a shoe, but also changes the appearance of the skate providing an armoured effect that is distinctive.

It will be understood that modifications, within the scope of the appended claims, may be made in the design and arrangement of the parts without departing from the spirit of the invention.

What is claimed is:

1. A roller skate comprising a platform having toe and heel sections, means for adjustably connecting the sections of the platform, rollers mounted on the heel and toe sections of the platform, a shield, U-shaped in plan mounted on the toe section of the platform, said shield having a projection at the forward end providing a toe stop and also having slots extended through side walls thereof, a key having notches in the edges extended through the slots in the side walls of the shield, a heel strap extended from the heel section of the platform, one end of the heel strap having a slot therein and the opposite end having notches in the edges positioned to coat with the slot for securing the ends together, and a heel stop depending from the outer end of the heel section of the platform.

2. In a roller skate, the combination which comprises a platform having toe and heel sections, means for adjustably connecting the toe and heel sections of the platform, rollers mounted on the sections of the platform, a U-shaped shield extended around the toe section of the platform and having an inclined leading surface with the lower edge extended downwardly providing a toe stop, said shield having vertically disposed slots extended through side walls thereof, a key having notches in the edges ex-

tended through the slots of the side walls of the shield providing holding means for the toe of a shoe on the toe section of the platform of the skate, the heel section having heel lugs extended upwardly therefrom and a depending flange providing a heel stop on the outer end, and a heel strap extended through the heel section and having a slot in one end and notches in edges of the opposite end whereby with the end having the notches therein extended through the slot the strap secures the heel section of the skate to a shoe or a foot of a wearer.

3. In a roller skate, the combination which comprises a platform having toe and heel sections, the sections being slidably connected, means for clamping the sections in adjusted positions, shafts mounted in bearings depending from the toe and heel sections of the platform, rollers positioned on the shafts, a plate, U-shaped in plan providing a shield extended around the toe section of the platform, means for securing the shield to the toe section of the platform, the forward end of the shield being inclined rearwardly from the lower end and having a depending flange providing a toe stop at the forward end, said shield also having a web extended across the upper surface and vertically disposed slots in side walls thereof, a strap having notches in the edges extended through the slots in the side walls of the shield for retaining the toe of a shoe on the toe section of the platform of the skate, the heel section of the platform having a depending flange with a sharp edge on the lower portion providing a heel stop, said heel section also having heel lugs extended upwardly from the upper surface and slots therethrough, and a heel strap extended through the slots in the heel section of the platform, the heel strap having a T-shaped slot in one end and notches in the edges of the opposite end whereby with the end having the notches in the edges thereof extended through the T-shaped slot of the other end the heel of the skate may be rigidly secured to the ankle of a foot the toe portion of which is secured below the strap extended through the slots in the side walls of the shield.

4. A roller skate comprising a platform having toe and heel sections, means for adjustably connecting the sections, pairs of wheels mounted on the sections, a shield U-shaped in plan, having side walls with slots in upper portions connected by an inclined forward end, mounted on the toe section of the platform, a strap having spaced notches in edges thereof extended through the slots in side walls of the shield, said slots being positioned at the ball of a foot in a shoe in the shield and being spaced above the platform a distance less than the height of the shoe whereby the shoe is gripped by the strap extended through the slots for securing the toe of a shoe in the shield and upon the platform, and a heel strap mounted in the heel section of the platform and having a T-shaped head on one end with a slot and notches in the sides of the opposite end positioned to receive the T-shaped head for securing the heel of the shoe in position on the platform.
